UNITED STATES PATENT OFFICE.

WILLIAM E. FRANK, OF ST. LOUIS, MISSOURI.

BED-SPRING.

1,163,905.

Specification of Letters Patent.

Patented Dec. 14, 1915.

Application filed July 3, 1914. Serial No. 848,864.

To all whom it may concern:

Be it known that I, WILLIAM E. FRANK, a citizen of the United States, and resident of St. Louis, Missouri, have invented certain new and useful Improvements in Bed-Springs, of which the following is a specification containing a full, clear, and exact description, reference being had to the accompanying drawings, forming a part hereof.

My invention relates to improvements in bed springs, in which a peculiarly woven wire fabric body is employed, in conjunction with a number of contractile coil springs supported by opposite rails of the rigid frame of the springs; and the objects of my improvements are first to provide a spring wherein all the "wire ends" are "covered" in order to obviate the "catching" of the felt mattress or bed clothes; and second, to provide a wire fabric possessing a maximum of elasticity in both longitudinal and transverse strands and to arrange the strands in such manner that there will be mattress distortion only at the point of the load.

I attain these objects by the construction of bed spring shown in the accompanying drawings, in which—

Figure 1 is a plan, with parts broken away, of a spring embodying my invention; Fig. 2 is a fragmental longitudinal sectional elevation, taken on the line 2—2 of Fig. 1; and Fig. 3 is a fragmental transverse sectional elevation taken on the line 3—3 of Fig. 1.

Referring by numerals to the accompanying drawings, 4 designates the side-rails and 5 the end rails which constitute the frame of the springs and which in their specific construction form no part of my invention.

At regular intervals in the end rails 5 I form perforations into which the hooked ends 6 of contractile coil springs 7 are inserted. At the opposite or inner ends each of the springs 7 is provided with a hook 8, each of which hooks 8 engage in a loop 9, which loop is one of a series, extending crosswise of the fabric and all formed from a single piece of wire.

Extending lengthwise of the bed springs are the longitudinal strands 10, arranged in pairs and having at intervals, registering with the loops 9, down-turned crimps 11,

which extend downwardly through said loops, with the bodies of the longitudinal strands next adjacent the loops resting on said loops.

The numerals 12—12 designate the border wires, lying at each side margin of the springs, over the side rails 4, having their ends inserted loosely into the coil springs 7 at the four corners of the springs, and their body portions between said springs bent outwardly to increase the spring surface laterally beyond said coil springs.

The reference numerals 13 designate transverse stay wires having at each end a hook 14, which hooks surround the border wires 12 and the bodies of the stay wires are extended beneath the loops 9 and over the crimps 11 of the transverse and longitudinal strands, thereby locking the said loops and crimps against relative vertical movements and at all times holding the loops and crimps together, under tension, in order to prevent catching and pinching of the mattress or bed clothing.

Having thus described my invention, what I claim as new therein and desire to secure by Letters Patent of the United States, is:

1. A fabric comprising longitudinal and transverse strands, the strands running in one direction having loops and the other strands having crimps extended through said loops, and stay wires intersecting said loops and crimps for binding the longitudinal and transverse strands into a fabric.

2. In combination with a rigid frame, a fabric comprising coil springs connected with opposite members of said frame, transverse strands having loops, certain of which are connected with said springs, longitudinal strands having crimps to extend into and through said loops, border wires at each longitudinal margin of the fabric, and stays having their ends connected with said border wires and interwoven with said loops and crimps to bind the whole into a fabric.

In testimony whereof, I have signed my name to this specification, in presence of two subscribing witnesses.

WILLIAM E. FRANK.

Witnesses:

E. L. WALLACE,
EDWARD E. LONGAN.
